INTERCHANGEABLE JEWEL MOUNTING

David Pfeffer, New York, N. Y.

Application May 22, 1946, Serial No. 671,623

4 Claims. (Cl. 63—29)

1

This invention relates generally to means for detachably mounting of precious and semi-precious stones in jewelry pieces.

The main object of the invention resides in the provision of a socket secured to a ring or other article of jewelry into which a variety of stones or gems may be detachably mounted without the use of special tools, or services of a person with specialized skill in the art of setting stones.

A further object of the invention resides in the provision of a socket of the above nature wherein a removable bezel frame adapted to firmly fix the stone or gem therein may assume a wide variety of designs and shapes to effectuate changes in the appearance of the stone or gem.

Another object of the invention resides in the provision of an article of jewelry wherein the consumer may replace stones and gems and wherein any particular stone or gem may assume different shapes and appearances by the use of a variety of differently designed bezel frames.

A further object of the invention resides in the provision of novel mounting means for stones and gems as applied to jewelry enabling the retailer to display a wide variety of jewelry with a minimum amount of stock.

Another object of the invention is to provide a novel means for assembling the various components of an article of jewelry having a stone or gem therein in a secure and permanent fashion.

A further object of the invention resides in the above detachable mounting assembly which eliminates the danger of breakage and chipping of stones by eliminating the use of special tools employed in conventional jewelry mounting.

These objects and other ends and advantages of the invention will hereinafter appear in the progress of the disclosure and as pointed out in the appended claims.

Accompanying this specification are drawings showing a preferred form of the invention wherein corresponding numerals designate corresponding parts throughout the several views and wherein:

Figure 1 is a view in elevation showing the mounting means as applied to a stone or gem in a finger ring.

Figure 2 is a top plan view of Figure 1.

Figure 3 is a sectional view of Figure 2 along the plane 3—3 thereof.

Figure 4 is a top plan view of Figure 1 with the stone and bezel frame removed therefrom.

Figure 5 is a bottom plan view of the bezel frame shown in Figure 1.

2

Figure 6 is an enlarged foreshortened sectional view taken along the plane 6—6 of Figure 5.

Figure 7 is a plan view of a modified form of bezel frame.

5 Figure 8 is an enlarged foreshortened sectional view taken along the plane 8—8 of Figure 7.

Figure 9 is a top plan view of another type of bezel frame.

10 Figure 10 is an enlarged foreshortened sectional view of Figure 9 along the plane 10—10.

Figure 11 is a top plan view of another modified type of bezel frame containing an ornamental design.

15 Figure 12 is a view in elevation showing a modified type of socket and bezel frame securing a stone therein as applied to a ring.

Figure 13 is a top plan view of Figure 12.

Figure 14 is an enlarged and fragmentary sectional view of Figure 12 taken along the band axis.

20 Figure 15 is a top plan view of the said modified type of socket as applied to a ring without a gem and bezel frame.

Figure 16 is a plan view of the bezel frame shown in Figure 12.

Figure 17 is a sectional view of Figure 16 along the plane 17—17 thereof.

25 In accordance with the invention and a form thereof shown in Figures 1—4, numeral 10 represents the band portion of a ring having spaced and opposite inclined terminals 11 and 12 to secure a box generally designated by numeral 13 and in which a stone or gem generally designated by numeral 14 is adapted to be mounted.

30 Box 13 is provided with opposing side and end walls 15, 15a and 16, 16a respectively to receive stone 14. As shown the lower parts of walls 15, 15a and 16, 16a incline inwardly such as in pyramid fashion while the upper parts 17, 17a and 18, 18a respectively are straight. A bottom wall 19 is provided for box 13 and as shown has a central opening 20.

35 A continuous shoulder 21 is formed on the inner surface of the box wall 15, 15a and 16, 16a by an expanded thickness thereof adjacent the bottom wall 19 while the straight walls 17, 17a and 18, 18a on the outer surface are reduced to

40 form a shoulder 22 which is adapted to seat a bezel frame 23 to demountably set stone 14 within the box 13 by means of raised and overhanging corner members 24.

45 Bezel frame 23 is provided with a groove 26 intermediate the ends of each wall thereof, the said groove being adapted to engage a corresponding projecting bead 25 intermediate and

50

55

along the outer face of each of the straight walls 17, 17a and 18, 18a.

The stone or gem generally designated by numeral 14 as shown has peripheral facets 27 and 28 which are adapted to engage with the walls 15, 15a and 16, 16a and the walls 17, 17a and 18, 18a of the box or socket 13. The bottom of stone 14 as designated by numeral 29 is adapted to sit on a shoulder 21 as best seen in Figure 3. It is to be noted that stone 14 projects above the tops of the straight walls 17, 17a and 18, 18a and for purposes of securing the stone in box 13 the bezel frame 23 is applied over the projecting portion of the stone whereby the overhanging corners 24 engage an upper peripheral facet 30 following the engagement between the groove 26 of bezel frame 23 with the projecting bead 25 along the straight wall portions 17, 17a and 18, 18a of socket or box 23. It is thus seen that bezel frame 23 engaging at the bottom the shoulders 22 and resiliently latching with the projecting beads 25 by means of the grooves 26 presents in conjunction with the corner members 24 a means for removably mounting a stone or gem in an article of jewelry in a simple, aesthetic and durable way. The overhanging corner members 24 which bear the gem 14 down against the socket may assume a variety of shapes as will hereinafter appear to present a stone of a uniform shape in a variety of designs. On the other hand a bezel frame such as that shown in Figures 1-4 may serve as the mounting means in conjunction with socket 13 for stones or gems of the same size and shape but of different colors and qualities. Moreover, the walls of socket 13 may form different geometric shapes to accommodate stones of corresponding geometric shapes and the bezel frames may also be shaped correspondingly. The latching means between the grooves 26 of the bezel frame 23 and the corresponding projecting beads 25 of the walls of box 13 may also vary in length, number and position.

In Figures 7 and 8 is shown a bezel frame 30a having an overhanging top wall with a rectangularly shaped aperture 31a and an inwardly directed flange 32 along the bottom and intermediate the length of each of the frame walls, each of the flanges 32 being adapted to be removably snapped over the bead 25 on the straight walls 17 of box or socket 13. A stone such as 14 set in place by the frame 30a appears rectangular in shape to the eye.

In Figures 9 and 10 is shown another type of bezel frame generally indicated by numeral 33 wherein the overhanging top wall 34 adapted to engage the top wall of the stone or gem has a substantially elliptical central aperture 35 to give a gem an elliptical appearance when set in the frame and wherein there are spaced inwardly directed flanges 36 along the bottom of each of the frame walls to be removably snapped over each of the beads 25.

In Figure 11 is shown still another type of bezel frame generally indicated by numeral 37 wherein the overhanging top wall 38 adapted to engage the top wall of the stone or gem is provided with cut-outs in the form of letters such as T-M so that the stone or gem 14 mounted in box 13 may appear in the form of letters, the inwardly directed flange 39 on the bottom of each of the walls 37 being varied in number.

In Figures 12-17 a ring having a band 40 is provided with a box or socket generally indicated by numeral 41 integral therewith or secured

thereto to receive a stone such as a polygonally shaped stone 42. Socket 41 has a lower conical wall portion 43 having a plurality of spaced inwardly directed shoulders each indicated by numeral 44 for the support of the stone's conical bottom wall 45, the said wall portion 43 terminating at the top in a cylindrical wall 46. At the top of wall 46 there is an inwardly directed flange 47 which proceeds upwardly to form a cylindrical wall 48. Spaced along wall 48 are a plurality of outwardly extending ears 49. A round bezel frame generally indicated by numeral 50 is adapted to secure stone 42 in socket 41 by being removably snapped over ears 49. The frame 50 has an overhanging top wall 51 having a central round aperture 52 the inner walls of which are conically shaped to set over the inclined peripheral facets 52 of stone 42 as best shown in Figure 14. The bottom wall of frame 50 has a bottom and inwardly directed circular flange 53 which is adapted to be removably snapped over ears 49 of the socket 41.

It is seen by the aforementioned description how any single item of jewelry may be provided with a setting comprised of a socket and bezel frame to accommodate a stone or gem of a corresponding shape with the socket for purposes of presenting the said stone or gem or a correspondingly shaped stone or gem to present a variety of appearances.

In accordance with the detachable setting means above described, any device used for removing a bezel frame from a jewelry piece may be used to remove the frame such as 23 from the socket 31 if the consumer objects to the use of his finger nail. Moreover such a device as a knife blade or a sharp edged tool when used is not proximate to the stone or gem and hence there is no danger of breakage and chipping thereof.

It is distinctly understood that minor changes and variations in the location, material, integration, shape and size of parts may all be resorted to without departing from the spirit of the invention and the scope of the appended claims.

45 I claim:

1. An article of jewelry including a base, a socket secured to said base, a decorative piece mounted in the socket, a frame having a top wall provided with an aperture and adapted to engage and expose portions of said decorative piece, the side and end walls of said frame having resilient detents, lugs on the socket for detachable engagement with said detents.

2. An article of jewelry including a base, a socket secured to said base, a decorative piece mounted in the socket, a frame having an overhanging top wall to secure said piece in the socket, the walls of said frame having resilient detaining means, means on the socket to cooperate with said detaining means and to serve as a latching device therewith.

3. An article of jewelry including a base, a socket secured to said base, a decorative piece mounted in the socket, a support inside and intermediate the height of the socket to seat said decorative piece, a frame having an overhanging top wall to secure said piece against the support in the socket, the walls of said frame having resilient detaining means, means on the socket to cooperate with said detaining means and to serve as a latching device therewith.

4. An article of jewelry including a base, a socket secured to said base, a decorative piece mounted in the socket, a frame having an overhanging top wall to secure said piece within and

2,436,120

5

against the socket, at least one of the walls of said frame having resilient detaining means, means on the socket to cooperate with said detaining means and to serve as a latching piece therewith.

DAVID PFEFFER.
